CHEMICAL FEEDER

Walter J. Hughes, Chicago, Ill., assignor to Infilco Incorporated, Chicago, Ill., a corporation of Delaware

Application January 6, 1949, Serial No. 69,500

12 Claims. (Cl. 103—38)

1

This invention relates to improvements in chemical feeders of the diaphragm type in which the displacement of the feeder is proportional to the stroke, and more particularly relates to a new and improved diaphragm pump adapted to accurately meter small quantities of chemical solutions.

The principal object of my invention is to provide a novel and simplified form of diaphragm pump controlled by a constant speed motor and so constructed and arranged as to effect a uniform flow of chemicals at various desired rates, with a high degree of accuracy.

Another object of my invention is to provide a diaphragm pump operated by fluid under pressure equally distributed over one face of the diaphragm so as to effect instantaneous operation of the diaphragm and so constructed and arranged as to produce a dwell between the strokes of the diaphragm, to effect a positive valve action upon each stroke of the diaphragm.

A more specific object of my invention is to provide a diaphragm pump in which the pressure strokes of the diaphragm are effected by the uniform application of fluid under pressure such as air, over one face of the diaphragm, to attain free and positive pressure stroke action of the diaphragm, and in which the diaphragm may be returned on its suction strokes by its own resiliency or by means of a spring, upon the release of pressure therefrom.

Another object of my invention is to provide a diaphragm pump having a novel form and arrangement of self cleaning check valves, so constructed as to attain positive opening and closing of the valves with a minimum obstruction to the flow of fluid through the valve ports, so as to attain free passage of fluid through the valve ports.

A further object of my invention is to provide a new and improved form of diaphragm pump wherein the valve ports, valves, pump chamber and diaphragm are so constructed and arranged as to provide a self-air-eliminating and self-priming pump against a substantial suction lift, as well as against a substantial discharge head.

Still another object of my invention is to provide a novel form of fluid pressure operated diaphragm pump utilizing a flexible diaphragm pre-formed in the shape it will assume at the ends of its suction strokes and uniformly conforming to the wall of the pump chamber at the ends of its pressure strokes, with a minimum amount of stretching, so as to secure uniform engagement of the diaphragm against the entire wall surface

2

of the pump chamber, and to assure complete evacuation of fluid therefrom.

A still further object of my invention is to provide a constant flow diaphragm pump which may be accurately regulated to attain various desired flows of liquid, and to provide a simple means for setting the rates of delivery thereof.

A further object of my invention is to provide a novel form of diaphragm pump in which the discharge of liquid may be quickly and easily regulated by varying the length of the strokes of the diaphragm.

Still another object of my invention is to provide a new and improved chemical feeder, including two pumps in a single casing operated from a single source of power and having independently controllable displacements, to dispense two different liquids.

These and other objects of my invention will appear from time to time as the following specification proceeds and with reference to the accompanying drawings wherein:

Figure 1 is a plan view of a chemical feeder constructed in accordance with my invention with part of the top cover removed and certain parts of the feeder casing shown in horizontal section;

Figure 2 is a longitudinal sectional view of a control valve for the chemical feeder, taken substantially along line 2—2 of Figure 1;

Figure 3 is an enlarged detail plan view of a rotatable valve disk used in the valve shown in Figure 2;

Figure 4 is a sectional view taken substantially along line 4—4 of Figure 3;

Figure 5 is a vertical sectional view of one of the pumps shown in Figure 1, and taken substantially along line 5—5 of Figure 1; and

Figure 6 is a vertical sectional view illustrating a modified form of pump constructed in accordance with my invention.

In the embodiment of my invention illustrated in Figure 1 of the drawings, two pumps 10 are shown as mounted on the outside of a casing 11 and extending thereinto. Each of said pumps may be of a similar construction so one only need herein be shown and described in detail. The casing 11 is provided with a removable cover 12 and has a motor 15 suitably mounted on its bottom. Said motor may be an electric motor of a constant speed type, and is connected to rotatably drive a pump control valve 16, mounted on the bottom of the casing 11, at one side of said motor. Said pump control valve 16 is herein shown as being of a rotary type and serves to

control the supply and release of fluid under pressure to operate the two pumps 10, through a pressure line 17, a T 18 and pressure lines 19 leading from opposite sides of said T to said pumps. While the two pumps 10 are herein shown as being supplied from a T and a single pressure line 17, it is readily apparent that individual pressure lines leading from separate ports in the valve 16 may be utilized as well. Fluid under pressure, such as air or liquid, may be supplied to the valve 16 for admission to and release from the pumps 10, through a fitting 20 connected with a head 21 of said valve, and communicating with a passageway 22 leading therethrough to a rotatable valve disk 27, seated against the inside face of said head. Said valve disk may be made from steel or brass or from one of the well known forms of anti-friction materials, one suitable material being that known to the trade as "Graphitar."

The valve disk 27 is rotatably driven from the motor 15 through a reducer 23, which may be of any well known type, so is not herein shown or described in detail. Said reducer is connected with the valve shaft 24 through a coupling 25. Said shaft 24 is journaled in a casing 26 for the valve and has a drive member 28 secured thereto. A sleeve 29 is mounted on and driven by said drive member and extends therefrom toward the head 21. The valve disk 27 is slidably mounted within said sleeve and has outwardly projecting pins 31, slidably engaging diametrically opposed slots in said sleeve. Said valve disk 27 is slidably engaged with the inner surface of the head 21 by a compression spring 30, seated in the member 28 at one of its ends and in the inner side of the valve disk 27 at its opposite end. The inner surface of the head 21 is accurately machined and ground to form a fluid tight seat for said valve, and said valve disk 27 is held against said seat by said spring at all times, so as to maintain a tight joint therebetween.

The valve disk 27, as herein shown, has a diametrically extending passageway 33 formed in its face, which slidably engages the seat formed by the inside of the head 21. Said passageway is closed by said seat and may be enlarged laterally at its opposite ends to give the required time for the pressure strokes of the pump. The inlet passageway 22 leading through the head 21, registers with the center of the passageway 33, so as to supply fluid thereto at all times. The pressure passageway 33 registers adjacent its ends with a pressure passageway 32 in the head 21, twice during each revolution of the valve disk 27. Said pressure passageway 32 extends through the head 21 from the inner to the outer side thereof and is suitably connected to the pressure line 17, to alternately admit fluid under pressure to and release fluid from the two pumps 10, to operate said pumps. The valve disk 27 is also provided with two exhaust passageways formed by diametrically opposed notches 35 extending therethrough. The exhaust passageways 35 serve to relieve pressure from the pressure passageway 32 and the pumps 10, twice during each revolution of said valve disk. Fluid released from the exhaust passageways 35 passes to the inside of the sleeve 29 and out through the slots formed in said sleeve, and through a relief opening 36, provided in the valve casing 26.

It should here be understood that the passageway 33 need not be diametrical and that its arrangement may be varied with respect to the discharge passageways 35, to change the timing

of the pumps, and that the elongated ends of said passageway may also be lengthened or shortened, to vary the time pressure is applied to operate the pumps 10, and to provide a dwell at the ends of the pressure and suction strokes of said pumps to insure instantaneous and positive opening and closing of the pump valves and an accurate displacement of the pump, as will hereinafter more clearly appear as this specification proceeds.

Each pump 10, as shown in Figure 5, includes a body or block 39 having a diaphragm 40 extending across its inner end, and clamped thereto by means of a head 41. Said head 41 is engaged with said diaphragm and may be secured to said body, as by machine screws 42. Said head 41 is herein shown as being flanged as indicated by reference character 43, and the flanged portion thereof is adapted to abut the outside of and be suitably secured to an outer wall of the casing 11, to support the body of said pump on the outside of said casing. The pressure and discharge ends of the pumps 10 are thus readily accessible, to facilitate the connection to and disconnection of chemical lines (not shown) to and from said pumps.

The body 39 of the pump 10 is provided with a pumping chamber 44 formed therein, in alignment with a recessed portion of the head 41, forming a pressure chamber 45, separated from the chamber 44 by the diaphragm 40. The pumping chamber 44 is herein shown as being of a concave substantially hat-shaped formation, with a relatively deep central depression and a slightly inclined annular brim.

The diaphragm 40 may be made of any well known elastic material, resistant to the chemicals to be fed, one form of material satisfactory for use in such pumps being neoprene. Said diaphragm may be preformed, as by molding, into the shape it will assume at the end of its suction stroke, so the yieldability of said diaphragm will urge it to move in the direction of its suction strokes, and to completely fill the pumping chamber 44 at the end of each pressure stroke. Said diaphragm, as herein shown, may have a flat brim which is clamped between the block 39 and head 41, and may have an annular inclined portion within said brim. Said inclined portion may extend at an opposite angle to the angle of the brim of the chamber 44, when said diaphragm is at the end of its suction stroke, to normally urge said diaphragm into the retracted position shown in Figure 5. Said diaphragm also has a central dome-shaped portion conforming to the central depression of the pumping chamber 44 and completely filling said depression at the end of each pressure stroke of the pump. The thickness of said annular inclined portion of said diaphragm increases slightly toward said dome-shaped central portion, to avoid the tendency of said diaphragm to bulge when pumping against a negative head, and to insure a uniform pumping action of said diaphragm under various pressure conditions.

A machine screw 47 is embedded in the enlarged central portion of the diaphragm 40 and extends within a spring chamber 49 formed in the head 41. A rod or spacer 50 is herein shown as being threaded on said machine screw and as extending within said spring chamber. A compression spring 51 is provided to move the diaphragm 40 on its suction strokes. Said spring is relatively light, and since the resiliency of said diaphragm 40 will urge it in the direction of its suction strokes, the spring could be dispensed

with when pumping under low heads. Said spring encircles the rod 50 and abuts the inner end of the spring chamber 49 at one of its ends. The opposite end of said spring abuts a disk or washer 53, secured to said rod 50 by a machine screw 54, threaded in said spacer. Fluid under pressure is admitted to the recessed portion 45 of the head 41, to actuate the diaphragm 40 on its pressure strokes, through a pressure passageway 55 extending through said head and connected with the pressure line 19. Substantial clearance is provided between the diaphragm 40 and the walls of the pressure chamber or recessed portion 45 of the head 41, when the diaphragm is at the ends of its suction strokes, to permit fluid under pressure to be uniformly distributed over one face of said diaphragm and instantaneously move it into uniform engagement with the wall of the chamber 44, so as to uniformly fill and completely evacuate said chamber at the ends of the pressure strokes of the pump.

Chemical solution is admitted to the pump chamber through an intake fitting 57. Said fitting has an enlarged annular inner end portion which abuts a valve guide 59 at its inner end. Said valve guide 59 is mounted in a shouldered end 60 of the valve body 39. The fitting 57 and valve guide 59 are secured to the valve body 39 by means of an internally threaded coupling 61, having engagement with an outer shouldered portion of said fitting. The passageway through the fitting 57 opens at its inner end into a valve chamber 62 formed by the enlarged inner end of said fitting. The inner end of the passageway through said fitting 57 serves as a valve port and is formed into an annular valve seat 63 spaced inwardly from the wall of the valve chamber 62. The annular seating surface of said valve seat 63 is of a convex formation and is adapted to be engaged by the outer edge of an inlet valve member 64, interposed between the valve guide 59 and seat 63. Said inlet valve member 64 may be made from a pliable material, such as neoprene, and is herein shown as being of a concave or umbrella-shaped formation, with a relatively thick inner portion tapering toward its periphery, so as to have a rigid interior and a pliable periphery. Pressure on said inlet valve member 64, during the pressure strokes of the diaphragm 40, will therefore firmly engage the outer pliable concave portion of said inlet valve member 64 with the convex surface of the seat 63, with a uniform sliding or wiping action. Said inlet valve member will thus wipe all foreign matter from the seat 63 upon closing, and the greater the pressure on said valve member from the chamber 44, the greater will be the seal between said valve member and seat. Said inlet valve member 64 has a stem 65 extending in a direction away from its concave portion, and slidably guided in the valve guide 59. The valve guide 59 is apertured as indicated by reference character 66, to allow for the free passage of liquid therethrough. An inlet passage 69 leads from the valve guide 59 to the pumping chamber 44 through the flat annular portion thereof, and extends to the concave portion of said pumping chamber.

A discharge passageway 70 leads from the concave portion of the pumping chamber 44 and connects the delivery side of said pumping chamber with a valve chamber 71, formed on the opposite end of the valve block 39 from the fitting 57. An annular valve seat 73, having a convex seating surface like the valve seat 63 is formed at the

outer end of said passageway 70. Said valve seat is adapted to be engaged by an outlet check valve member 74, which is of an umbrella-shaped formation, formed like the inlet valve member 64 and slidably guided in a valve guide 75, spaced outwardly from said valve seat. The valve guide 75 is held in position in the valve block by means of a fitting 76 abutting the outer face of said guide, and a coupling 77 threaded in an end of said block and engaging said fitting. Said outlet valve member 74 is thus engaged with the valve seat 73 with a sliding or wiping action by the suction created in the chamber 44, upon the suction strokes of the pump and forms a self-cleaning positively acting check valve.

It may be seen from the foregoing that the check valves just described are of a light pliable construction so as to instantaneously open and close with a minimum amount of pressure and suction, upon the suction and pressure strokes of the pump, to permit the free flow of liquid into and from the pump, and that the valve 16 is so constructed as to provide a positive dwell at the ends of the suction and pressure strokes of the pump, to cause said check valves to instantaneously and positively act to open or close the desired port. Also, said check valves, being of a pliable construction, become more firmly seated the greater the suction or pressure exerted thereon, and when the pump is in the position shown in Figure 5 close their respective passageways when the pump is not in operation. This avoids siphoning through the pump and avoids the trapping of air therein, and also assures the retention of liquid in the pump chamber, brought therein upon the suction strokes of the pump by the action of the spring 41. The pump 10 will thus be self-priming and will immediately start pumping upon operation of the diaphragm 40.

A means is provided to accurately control the rate of discharge of the pump, which is herein shown as being a square threaded screw 79, movable to form an adjustable stop for the diaphragm 40, and to vary the lengths of the suction strokes thereof. Said screw is herein shown as being threaded within an internally threaded spacer 80, secured to the outer end of the head 41. Said screw is also feathered on a shaft 81, journaled in a cap 83, secured to said spacer and abutting the outer end thereof. A disk 84 is secured to the outer end of said shaft, to rotatably move said shaft and move the screw 79 with respect to the disk 84. Said disk 84, as shown in Figure 1, may extend through a slot 85 formed in the cover 12, and may be calibrated along its outer periphery with respect to an indexing mark on said cover, to designate the desired flow of solution through the pump. The displacement of the pump may therefore be accurately adjusted from the outside of the casing at will. The pitch of the threads of the screw 79 may be such that one revolution of said disk 84 may move said screw from an extreme inward position, where there will be no flow of liquid through the pump, to the extreme outward position shown in Figure 5, where there will be a maximum flow of liquid through the pump.

In operation, the motor 15 is started to operate the feeder. This will rotatably drive the valve disk 27 and admit fluid under pressure to each pump through the passageways 33, 32 and the pipes 17 and 19. Twice during each revolution of said valve disk 27, fluid under pressure in the pressure chamber 45 will act on the diaphragm 40 throughout its effective area, to instantane-

ously move said diaphragm on its pressure strokes. Upon each pressure stroke of the pump, pressure in the chamber 44 and passageways 69 and 70 will close the inlet check valve 64 and open the discharge check valve 74, to permit the passage of liquid therethrough and through the fitting 76, for use. The exhaust passageway 35 formed in the valve disk 27 will also register with the passageway 32 twice during each revolution of said valve disk 27. This will relieve pressure from the chamber 45 and permit the spring 51 to move said diaphragm 40 on its suction strokes. During the suction strokes of said diaphragm, suction in the pumping chamber 44 will open the check valve 64 and will close the check valve 74.

In the modified form of my invention shown in Figure 6, the pump is somewhat similar to that shown in Figure 2 except that a second diaphragm 87, of a larger effective area than the diaphragm 40, is provided. This form of my invention requires less pressure to operate the pump than is required to operate the pump shown in Figure 5 and is particularly adapted for use where it is necessary to lift against greater heads than could be efficiently handled by the pump shown in Figure 5. The pump shown in Figure 6 is of the same general construction as that shown in Figure 5, so a description of the parts described before need not be repeated, and the same part numbers have been applied to similar parts in each of said figures. In Figure 6, the pump is shown as having a flanged head 88, which clamps the diaphragm 40 to the valve block 39. A spacing member 89 is secured to said diaphragm by means of the machine screw 47. Said spacing member has a flanged outer end and is encircled by a spring 90, seated within a recessed portion of the head 88 at one of its ends, and abutting the flanged portion of said spacing member at its opposite end, and urges the diaphragm 40 in a direction away from the chamber 44, to effect the suction strokes thereof, upon the release of pressure from the diaphragm 87. A hollow flanged member 93 is shown as being secured to the outer side of the head 88 as by machine screws 94. While the flanged member 93 and head 88 are herein shown as being separate parts, it should be understood that they may as well be integrally formed. The hollow inside portions of said flanged member and head form a chamber open to the atmosphere, within which the spacing member 89 moves. The outer end of said chamber is closed by the diaphragm 87 extending thereacross. Said diaphragm 87 may be made from any resilient or pliable material, and is preformed into the shape it will assume at the ends of its suction strokes. Said diaphragm 87 is clamped into engagement with the flanged portion of said flanged member by means of a cap 95, secured to said flanged member 93 by machine screws 99. Said cap has a central recessed portion 96 forming a pressure chamber, the outer wall of which is spaced from the diaphragm, when said diaphragm is in a retracted position, to provide clearance and permit fluid under pressure to uniformly engage said diaphragm throughout its entire area at the beginning of the pressure strokes of the pump. A diaphragm plate 100 serves to clamp said diaphragm to the flanged portion of the spacing member 89, to cause said diaphragm to positively move said spacing member and the diaphragm 40 on its pressure strokes, upon the application of pressure to the diaphragm 87 in the chamber 96. Said diaphragm plate 100 is held in engagement with said diaphragm

87 by a machine screw 101, threaded in the outer end of the spacing member 89. A pressure passageway 103 enters the chamber 96, to supply pressure to said diaphragm and positively move said diaphragm 40 on its pressure strokes, against the spring 90. The suction strokes of said diaphragm 40 are effected by means of the spring 90 upon the release of pressure from the chamber 96, through the pressure passageway 103. A threaded stop 105 is adapted to engage the retaining plate 109, to adjustably limit the suction strokes of said diaphragm 40. Said stop is threaded within the cap 95 and is feathered on a shaft 106, journaled in an end closure member 107 for the cap 95. Said shaft and stop may be operated by a control disk like the disk 84 (not shown).

It may now be seen that a novel form of chemical pump of a simplified and improved construction has been provided, to accurately feed small quantities of chemical solution proportional to the stroke of the pump, which includes a preformed diaphragm, formed so as to be urged in the direction of its suction strokes by its own resiliency and to completely fill the pumping chamber with a minimum amount of stretching upon its pressure strokes, so as to positively evacuate all of the liquid from said pumping chamber at the end of each pressure stroke.

It may further be seen that said diaphragm is actuated on its pressure strokes by the uniform application of fluid under pressure thereto throughout its entire area, and may be returned on its suction strokes by its own resiliency or may be returned by means of a spring when pumping against a substantial head, and that the valve controlling the admission and release of fluid under pressure to and from said diaphragm is so arranged as to provide a dwell at the end of each pressure and suction stroke, so as to secure an instantaneous and more positive action of the pump valves than formerly and thus to increase the accuracy of the pump.

It may also be seen that the inlet and outlet valves of the pump are of a simplified form of yieldable check valve, so arranged as to permit the free flow of liquid therethrough, and to positively engage their respective seats with a uniform wiping action, so as to keep the valve seats clean by the wiping action of the valve and to assure that there will be no leakage of liquid thereby, when in closed positions.

It may still further be seen that this arrangement of valves and diaphragm assures the utmost accuracy in pumping the desired quantities of solutions and avoids siphoning when the pump is not in operation, and also assures that the pump be self-priming and self-air-eliminating.

While I have herein shown and described several forms in which my invention may be embodied, it should be understood that I do not wish to be construed as limiting myself to the forms shown, except as expressly limited in the appended claims.

I claim:

1. In a chemical feeder, a casing having a concave inner wall forming a pumping chamber, a head for said casing having a recessed portion in alignment with said chamber, an elastic diaphragm extending across said casing and clamped in position by said head, said diaphragm being preformed in the shape it will normally assume at the ends of its suction strokes and to uniformly conform to the contour of said chamber without substantial stretching at the ends of

its pressure strokes, to completely evacuate liquid therefrom, a valved liquid inlet to and a valved liquid outlet from said pumping chamber, a spring seated in said head and operatively connected with said diaphragm, to move said diaphragm on its suction strokes, an inlet into said recessed portion of said head, means including a motor driven valve for alternately admitting fluid under pressure to and releasing pressure from said inlet, to move said diaphragm on its pressure strokes, and to permit said spring to move said diaphragm on its suction strokes, clearance being provided between said recessed portion of said head and said diaphragm when said diaphragm is at the extreme ends of its suction strokes, to permit pressure to be uniformly distributed over the face of said diaphragm opposite from said chamber at the beginning of its pressure strokes.

2. In a chemical feeder, a casing having a concave inner wall forming a pumping chamber, a head for said casing having a recessed portion in alignment with said pumping chamber, an elastic diaphragm extending across said chamber and clamped in position by said head, said diaphragm being preformed in the shape it will normally assume at the ends of its suction strokes and being arranged to conform to the contour of said chamber at the ends of its pressure strokes without substantial stretching, to completely evacuate liquid therefrom, a valved liquid inlet to said pumping chamber, a valved liquid outlet therefrom, a spring operatively connected with said diaphragm to move said diaphragm on its suction strokes, a fluid pressure inlet into said recessed portion of said head, means for alternately connecting said fluid pressure inlet to a source of fluid under pressure and to atmosphere, said means including a motor driven valve connected to said inlet, the inner wall of said recessed portion of said head being spaced from said diaphragm to provide clearance between said diaphragm and said inner wall at the ends of its suction strokes to uniformly distribute pressure over the face of said diaphragm opposite from said pumping chamber at the beginning of its pressure strokes, and a stop adjustable to vary the length of the strokes of said diaphragm and the displacement of said pump.

3. In a chemical feeder, a casing having a concave inner wall forming a pumping chamber, a head for said casing, an elastic diaphragm extending across said casing and pumping chamber and clamped in position therein by said head, said diaphragm being preformed into the shape it will normally assume at the end of each suction stroke and to uniformly conform to the contour of said inner wall at the end of each pressure stroke without substantial stretching, a spring operatively connected with said diaphragm to move said diaphragm on its suction strokes, valve means adapted to admit fluid under pressure to the side of said diaphragm opposite from said pumping chamber to move said diaphragm on its pressure strokes, a screw threaded within said head and adapted to form a stop for said diaphragm on its suction strokes and to determine the length of the strokes of said diaphragm and the displacement of said pump, a manually operable control disk for rotating said screw, the pitch of said screw being such that one complete revolution of said disk will adjust the strokes of said diaphragm from a no-pumping condition to a maximum pumping condition.

4. In a chemical pump, a casing having a chamber formed therein, a flexible diaphragm divid-

ing said chamber into a pumping chamber on one of its sides and a pressure chamber on its opposite side, a fluid pressure inlet to said pressure chamber, a spring connected with said diaphragm to move said diaphragm on its suction strokes, said pumping chamber being of a substantially hat-shaped form with a relatively deep concave central depression and an annular flatly inclined brim leading from the edge thereof, said diaphragm being preformed in the shape it will normally assume when completely retracted at the ends of its suction strokes and having a central convex projecting portion conforming to the form of said concave central depression of said pumping chamber and adapted to completely fill said central depression at the end of each pressure stroke of the pump, and said diaphragm having an annular flatly inclined portion extending outwardly from said central convex portion at the same angle to the horizontal as said annular brim of said pumping chamber, but extending in an opposite direction to the horizontal when said diaphragm is in a retracted position so as to urge said diaphragm in the direction of its suction strokes by its own resiliency, clearance being provided between said diaphragm and the walls of said pressure chamber to uniformly distribute pressure over the entire face of said diaphragm adjacent said pressure chamber at the beginning of its pressure strokes.

5. In a chemical pump, a chamber having a concave inner wall, a reciprocable flexible diaphragm extending across said chamber and formed to conform to the shape of said concave wall when in an extended position, and dividing said chamber into a pressure chamber on the side of said diaphragm opposite said concave wall and a pumping chamber on the side of said diaphragm adjacent said concave wall, a liquid inlet to said pumping chamber, a liquid outlet therefrom, valve means in said inlet and said outlet, a spring operatively connected with said diaphragm to move said diaphragm on its suction strokes, a fluid inlet to said pressure chamber, means for alternately supplying fluid under pressure to and releasing fluid from said pressure chamber including a motor driven valve, a stop screw adapted to determine the length of the strokes of said diaphragm and the displacement of said pump, and a control wheel operatively connected to rotate said screw, the pitch of said screw being such that one revolution of said control wheel will vary the length of the strokes of said diaphragm from a no-pumping condition to a maximum pumping condition.

6. In a chemical pump, a pumping chamber, a reciprocable diaphragm extending across said chamber and preformed into the shape it will assume at the ends of its suction strokes and to completely fill said chamber at the ends of its pressure strokes without substantial stretching, spring means for operating said diaphragm on its suction strokes, an inlet to and an outlet from said pumping chamber, check valves in said inlet and said outlet, each of said check valves including a check valve member and an annular valve seat, means to assure complete and instantaneous opening and closing of said check valves and an accurate displacement of said pump including a motor driven valve connected to admit fluid to operate said diaphragm on its pressure strokes and to release fluid therefrom at the beginning of its suction strokes, said motor driven valve being so constructed and arranged

as to provide predetermined dwells at the ends of the strokes of said diaphragm to assure positive and instantaneous opening and closing of said valves, said check valve members being of a pliable umbrella-shaped formation adapted to engage their respective valve seats with a uniform wiping action.

7. In a chemical pump, a pumping chamber, a reciprocable diaphragm extending across said chamber and preformed into the shape it will assume at the ends of its suction strokes and to completely fill said chamber at the ends of its pressure strokes without substantial stretching, spring means for operating said diaphragm on its suction strokes, an inlet to and an outlet from said pumping chamber, check valves in said inlet and said outlet including an annular valve seat therein having a convex seating surface and a pliable check valve member engageable with said seating surface, said check valve members being of an umbrella-shaped formation and having guide stems extending therefrom in directions away from their seats, and means to assure complete and instantaneous opening and closing of said check valves in the desired sequence and an accurate displacement of said pump including a motor driven valve connected to admit fluid under pressure to operate said diaphragm on its pressure strokes and to release fluid therefrom at the beginning of its suction strokes, said motor driven valve being so constructed and arranged as to provide predetermined dwells at the ends of the strokes of said diaphragm to assure positive and instantaneous opening and closing of said check valves upon reversal of the strokes of said diaphragm.

8. In a chemical pump, a pumping chamber having a concave inner wall, a reciprocable diaphragm extending across said chamber and preformed into the shape it will assume at the ends of its suction strokes and to completely fill said chamber when in an extended position without substantial stretching, spring means for operating said diaphragm on its suction strokes, an inlet to and an outlet from said pumping chamber, check valves in said inlet and said outlet, each of said check valves including an annular valve seat with an annular convex seating surface, a valve guide spaced from said seat, a pliable check valve member of an umbrella-shaped formation interposed between said guide and said seat, said check valve member having a stem extending from one of its sides and guided in said valve guide, and having an opposite concave side slidably engageable with said convex seating surface of said valve seat with a uniform wiping action, and means assuring positive and instantaneous opening and closing of said check valves in the desired sequence and an accurate displacement of said pump including motor driven valve means connected to admit fluid under pressure to operate said diaphragm on its pressure strokes and to release pressure therefrom at the beginning of its suction strokes, and being so constructed and arranged as to provide predetermined dwells at the ends of the strokes of said diaphragm to assure positive and complete opening and closing of said check valves upon the reversal of the strokes of said diaphragm.

9. In a chemical pump, a casing, two spaced diaphragms in said casing connected to move in unison and separating said casing into a pumping chamber on one side of one diaphragm, a pressure chamber on the opposite side of the other diaphragm, and a spring chamber be-

tween said diaphragms and connected to atmosphere, a spring in said spring chamber connected to move said diaphragms in one direction, said diaphragms being preformed into the shapes they will normally assume at the ends of their suction strokes, said one diaphragm being so shaped as to completely fill said pumping chamber at the end of its pressure strokes without substantial stretching, and said other diaphragm having a larger effective area than said one diaphragm, valved inlets and outlets to and from said pumping chamber, a pressure inlet to said pressure chamber, means for alternately connecting said inlet to a source of fluid under pressure and to atmosphere, and clearance being provided between the walls of said pressure chamber and the adjacent face of said other diaphragm, whereby pressure may be uniformly applied to the entire area of said other diaphragm at the beginning of the pressure strokes of the pump.

10. In a chemical pump, a casing, two spaced diaphragms in said casing connected to move in unison and separating said casing into a pumping chamber on one side of one diaphragm, a pressure chamber on the opposite side of the other diaphragm, and a spring chamber between said diaphragms and connected to atmosphere, a spring in said spring chamber connected to move said diaphragms in one direction, said diaphragms being preformed into the shapes they will normally assume at the ends of their suction strokes and being urged in the direction of their suction strokes by their own resiliency, and said diaphragm separating a part of said casing into a pressure chamber having a larger effective area than said diaphragm separating a part of said casing into a pumping chamber, and said diaphragm separating a part of said casing into a pumping chamber being so shaped as to completely fill said pumping chamber at the ends of its pressure strokes without substantial stretching, valved inlets and outlets to and from said pumping chamber, a pressure inlet to said pressure chamber, means for alternately connecting said inlet to a source of fluid under pressure and to atmosphere, clearance being provided between the walls of said pressure chamber and the adjacent face of its associated diaphragm, whereby pressure may be applied to the entire area of said associated diaphragm at the beginning of the pressure strokes of the pump, and an adjustment screw forming a stop to vary the length of the strokes of said diaphragms and the displacement of said pump.

11. In a chemical pump including a pumping chamber, a reciprocable pumping member, means for reciprocating said pumping member into and out of said pumping chamber, an inlet to said pumping chamber and an outlet from said pumping chamber, self-cleaning check valves in said inlet and said outlet, each of said check valves comprising an annular valve seat having a convex seating surface, an umbrella-shaped valve member having a concave side facing said seat, said concave side being uniformly curved from its periphery to its center, said member being of pliable material and having a relatively thick center portion tapering toward a thin peripheral portion to provide a relatively rigid interior and a pliable peripheral portion, said peripheral portion when under pressure engaging said convex seating surface with a uniform wiping action, a valve stem extending from said center portion

in a direction away from said valve seat, and a valve guide for said stem.

12. In a chemical pump including a pumping chamber, a reciprocable pumping member, means for reciprocating said pumping member into and out of said pumping chamber, an inlet to said pumping chamber and an outlet from said pumping chamber, self-cleaning check valves in said inlet and said outlet, each of said check valves including an annular valve seat with an annular convex seating surface, the combination with said seating surface of an improved check valve member of pliable material, said check valve member being of an umbrella-shaped formation with a concave side facing said seat, said 15 concave side being uniformly curved from its periphery to its center, the peripheral portion of said check valve member being thin and flex-

ible, and, when under pressure, slidably engageable with said convex seating surface of said valve seat with a uniform wiping action.
